UNITED STATES PATENT OFFICE.

ADOLPH K. MALMQUIST, OF SOUTH BELLINGHAM, WASHINGTON, ASSIGNOR TO
DEMING & GOULD COMPANY, OF SOUTH BELLINGHAM, WASHINGTON.

ART OF CANNING.

1,386,887.

Specification of Letters Patent. Patented Aug. 9, 1921.

Application filed November 13, 1919. Serial No. 337,737.

To all whom it may concern:

Be it known that I, ADOLPH K. MALMQUIST, a citizen of the United States, and resident of South Bellingham, in the county 5 of Whatcom and State of Washington, have invented certain new and useful Improvements in the Art of Canning; and I do hereby declare the following to be a full, clear, and exact description of the invention, such 10 as will enable others skilled in the art to which it appertains to make and use the same.

This invention relates to improvements in the art of canning, and more particularly to 15 the canning of materials including liquids,—especially when liquids are introduced into cans which contain edible solids.

In the canning of fruits and vegetables, it is customary to introduce into the can 20 with such solids, a quantity of liquid, such as syrup and it is desirable that the can shall be filled as near completely as possible, and it is also desirable that the fruit or vegetable shall retain the natural flavor and color.

25 It has heretofore been proposed to first fill cans with a desired amount of solids, and then, after completing the filling of the can with liquid, to pass the same through a steam box with the object of heating the solids so 30 that the liquid will permeate the same.

When the cans are sealed while hot and then cooled, a slight vacuum is formed, but in heating the cans in the manner above described, the contents will swell and the liquid often overflows, thus causing a loss and 35 leaving the cans partly filled, and furthermore, the heating causes the contents of the can to lose a portion of its flavor and also to become more or less discolored.

40 One object of my invention is to supply cans containing solid edibles, with liquid and sealing the cans, in such manner as to avoid heating the contents of the can; so that the pores of the fruit or other solid shall 45 be opened to facilitate permeation of the liquid; so that overflowing and consequent loss of liquid will be avoided, and so that the cans shall be completely filled.

A further object is to so "syrup" and seal 50 cans that both the "syruping" and sealing shall be accomplished while the can occupies a vacuous or exhausted chamber.

With these and other objects in view, the invention consists in certain novel features

as hereinafter set forth and pointed out in 55 the claims.

In the accompanying drawings, Figure 1 is a sectional view of a machine whereby my invention can be carried into effect. Fig. 2 is a sectional view on the line 2—2 of Fig. 1 60 showing the positions of the parts when a can containing solids is first introduced into the machine. Fig. 3 is a view similar to Fig. 2 showing the relations of the parts when the can is positioned to receive liquid. 65 Fig. 4 is a sectional view on the line 4—4 of Fig. 1 showing the relations of the parts when the can is positioned to be sealed with a cap, Fig. 5 is a horizontal section; Fig. 6 is a front view, and Figs. 7, 8, 9, 10, 11 and 70 12 are views showing various details.

1 represents framework on which a casing 2 is mounted, said casing providing a chamber 3 in which both the filling of the can with liquid and the sealing of the can is 75 accomplished. Rubber or other packing 4 may be provided for the ends of the casing and a movable closure 5 is provided for the front of the casing and a packing 6 provides an airtight fit for said closure 80 against the casing. The closure 5 carries slides 7 which project in both directions from its lower edge and these sides are movable in guides 8 secured to the framework 1. A latch plate 9 is pivotally mounted on the 85 closure 5 and is provided with lugs 10 to co-operate with lugs 11 fixed to the casing 2 for locking the closure in place.

Located within the lower portion of the chamber 3 are two vertically movable platforms or plunger heads 12 and 13 and between these platforms or plunger heads, a vertically adjustable platform 14 is disposed,—the latter having a shank 15 which passes through a tubular guide 16 depending 90 from the casing 2 and is adjustably secured to said guide by a screw 17. The platform 12 (which may be square) is provided with a tubular stem 18 which enters the tubular portion of a plunger 19 and said platform is 95 also made with an annular flange 20 forming a groove into which the upper end of the plunger enters. A plunger 21 passes through the central portion of the platform 12 and through the tubular stem 18 and the 100 tubular portion of the plunger 19,—the lower portion of said plunger 21 being threaded to enter a threaded socket 22 in

the lower portion of the plunger 19, and prevented from turning by a screw 21^a. The upper end of the plunger 21 is provided with a head 23 normally seated in a socket or 5 recess 24 in platform 12. A spring 25 is located within the plunger 19 and around the plunger 21,—one end of said spring bearing against the lower end of the tubular stem 18 of the platform 12 and the other end 10 of said spring resting on a shoulder 26 within the plunger 19. The plunger 19 passes through a tubular guide 27 depending from the casing 2, and is provided with an annular groove 28 for the accommodation of a 15 split ring 29.

The lower end of the plunger is pivotally connected to an operating lever 30, the latter being pivotally connected with the framework 1, and a cam-lock 31 pivoted to 20 said lever and coöperable with an adjustable screw or abutment 32, serves to lock the lever in raised position when said lever shall have been operated to elevate a can resting on the platform 12 for relieving syrup or 25 other liquid as hereinafter explained.

The platform 13 (which may be circular) is provided with a stem 33 which enters the tubular portion of a plunger 34 and an annular flange 35 depending from said platform 30 surrounds the upper end portion of said plunger. The stem 33 is made with an annular groove 36 into which a screw 37, passing through the wall of the plunger 34, enters—the size of said groove relatively to 35 that of the screw being such as to permit a limited longitudinal movement of the stem 33 (and hence the platform 13) relatively to the plunger 34, and to permit said platform to rotate. A block 38 is mounted 40 freely within the tubular portion of the plunger 34 and connected with the latter through the medium of a pin-and-slot construction indicated at 39. A ball bearing 40 is provided between the lower end of the 45 platform stem 33 and the block 38, and between said block and the lower end of the tubular portion of the plunger 34, a spring 41 is disposed. The plunger 34 passes freely 50 through a tubular guide 42 depending from the casing 2 and an annular groove in said plunger receives a split ring 43.

The lower end of the plunger 34 is pivotally connected with an operating lever 44, the latter being pivoted to the framework at 55 45, and by raising this lever the platform 13 may be raised to elevate a can and present the same and a cap to sealing mechanism, as hereinafter explained. An arm 44^a depends from the lever 44 and engages a 60 screw 44^b. By adjusting the screw 44^b, the height of the platform 13 and the desired tension for the seaming operation of the cap to the can may be adjusted.

During the operation of supplying syrup 65 or other liquid to the can and the subse-

quent capping or sealing of the can while the latter is within the chamber 3, it is important that the latter shall be so exhausted of air as to form a partial vacuum. For this purpose, a pipe 46 connects the chamber 3 70 with a suitable exhaust pump (not shown), and a valve 47 is provided for this pipe. A pipe 48 also communicates with the chamber 3 and is provided with a vacuum release valve 49, whereby air may be admitted to 75 said chamber after the exhaust valve 47 shall have been closed.

A plate 50 is disposed over an opening in the top of the casing 2 and formed with a valve casing 51 and an externally threaded 80 nipple 52, said valve casing and nipple having a vertical duct 53 communicating with the chamber 3 in the casing 2. A plug valve 54 is mounted in the casing 51 for opening and closing the duct 52, and is provided with a stem 55 having an operating cross-head or handle 56 at one end. One end of the valve is provided with a short stem 57 passing through the wall of the casing and threaded to receive a nut 58, and a spring 59 is located on the main stem 55 of said valve between the casing 51 and a collar 60 pinned to said stem near the cross-head or handle 56. The upper end of the valve casing 51 receives a pipe 61 leading from a suitable 95 source of supply of syrup or other liquid. When the filling liquid is a heavy syrup, it will be desirable to warm the same somewhat before it passes through the valve in order to avoid thickening, or crystallization of the sugar which might tend to clog the valve. For the purpose of warming the syrup, a heating jacket 61^a may be located around a portion of the pipe 61 and provided with an inlet 61^b for a heating medium, and with a 100 drain cock 61^c.

A gasket 62 of rubber or other suitable material is located on the under side of the base plate 50 of the valve casing and below this gasket a ring 63 having a smooth face 110 is located and provided with a flange entering a central opening in said gasket, said ring being screwed onto the nipple 52 and being of such thickness as to compensate for the depth of a can cap. A ring 64 depends into the casing 2 and is provided with a flange 65 resting upon said casing under the gasket 62, said ring serving as a guide for a can and to prevent escape of the solid contents over the edge of the can and said ring 115 is provided with holes 66 forming air passages.

A rack bar 67 is suitably mounted to slide through a guide 67^a within the chamber 3, and to this rack-bar, a yoke or can-holding bracket 68 is secured, and adapted to receive a can on the platform 12. Brackets 69 are secured to the closure 5 and to these brackets, guide bars 70 are secured and serve to retain the can properly in the yoke or bracket 68. 125 130

A pinion 71 is provided for operating the rack-bar and is carried by a shaft 72 passing through suitable bearings in a housing 73 projecting from the casing 1, said shaft 5 being provided at its outer end with hand operating means 74.

A can 75 filled with fruit or other solid edibles and minus a cap or cover, is placed on the platform 12 and in the yoke or bracket 68 as indicated in Fig. 2, after which the closure 5 will be moved to close the chamber 3 air-tight. The release valve 49 being closed, the valve 47 may now be opened and the chamber 3, as well as the can and its 15 contents will be exhausted of air,—thus causing the pores of the fruit to be opened to permit permeation of liquid subsequently introduced. The lever 30 will now be operated to raise the platform and the can thereon. 20 During the rising of the can, its upper open end will be guided by the ring 64 (said ring also serving to prevent escape of any of the contents of the can) and finally the upper end of the can will be pressed against the 25 gasket 62, and the ring 63 will press the fruit sufficiently to compensate for the depth of a cap or cover to be subsequently applied. When the can shall have been raised as above described, it will be held in its raised 30 position by the operation of the cam lock 31 and the height to which the platform 12 on which the can is supported, may be raised, may be adjusted by means of the screw 32 with which the cam lock coöperates. 35 The valve 54 may now be opened to permit the syrup or other liquid to flow (under atmospheric pressure) into the can, and fill the spaces between the pieces of fruit and to effectually permeate the fruit, the pores 40 of which, due to the vacuous condition which exists, will be open to receive the liquid.

When the can was being raised and its upper end pressed against the seat or gasket 62 by the action of the plunger 19 and 45 platform 12, the plunger 21 moved slightly farther than the platform 12 and pressed or bowed the bottom of the can upwardly as indicated at 76, Fig. 3, thus reducing the capacity of the can somewhat,—this reduction 50 of capacity being equal to the capacity of that portion of the liquid duct 53 below the valve 54. If this provision for reducing the capacity of the can were not made, the amount of fluid in the lower portion of the 55 duct 53 would be sucked out when the can begins to lower and would probably overflow the can, and be lost, but when the plunger begins to move downwardly, the plunger 21 will descend prior to the descent 60 of the platform 12 and the bottom 76 of the can will straighten out, thus increasing the capacity of the can sufficiently to receive the surplus syrup in the lower portion of the duct 53. The can may now be lowered, but 65 as the degree of vacuum in the can will have

been reduced below the degree of vacuum in the chamber 3 and hence in order to prevent the liquid from being sucked out of the can, the degree of vacuum in the chamber must be reduced to or below the degree of vacuum 70 in the can. This can be readily accomplished by opening the release 49 slightly. The can can now be lowered to the position shown at the right of Fig. 1 without danger of losing any of its contents. 75

The heights of the platforms 12, 13 and 14 having been properly adjusted so their upper surfaces will be in alinement, the can will be moved while in the exhausted chamber 3, from the platform 12, over the intermediate platform 14 and onto the platform 13, which operation is accomplished through the medium of the rack-and-pinion gearing hereinbefore described. When the can shall have been properly positioned upon the platform 13 it will be raised to the cap seaming mechanism by operation of the lever 44 and the cap will be seamed to the can while the vacuous condition is maintained within the 80 chamber 3. 85

The construction and operation of the seaming mechanism will now be explained.

A bracket 77 is located upon the casing 2 and is provided with a boss 78 which enters an opening in the top of said casing, and secured to the boss 78, within said opening, is a cap abutment or holding ring 79, which depends into the chamber 3 and is recessed for the accommodation of a chuck 80 having a recess in its under face. The chuck 80 is 100 located at the lower end of a tubular spindle 81 mounted in a bearing sleeve 82 which may form part of the bracket 77 and a suitable gland 83 is provided within the bearing sleeve for the spindle. The tubular spindle 105 81 also passes through a cross-head 84, located upon the bracket 77 and the upper portion of said spindle is threaded to receive nuts 85. A rod 86 passes through the tubular spindle 81 and is provided at its lower 110 end with a head 87 normally seated in the recess in the chuck head 80 and held therein by a spring 88 encircling the upper projecting end of the rod 86,—said spring bearing at one end against the tubular spindle 81 and at the other end against a collar 89 keyed to said rod. The rod 86 with its head 87 may be employed to release the capped can from the sealing means in the event of binding or sticking of the same to said sealing means. 115 120

An annular holder 90 for a can cap 91 is located below the chuck 80 and is secured to one of the brackets 69. Seaming rollers, such as indicated at 92 are mounted on a bracket 93 carried by the upper end of a 125 vertical shaft 94 located within the casing 2. This shaft 94 depends below the casing 2 and is provided with an operating lever 95 for controlling the relation of the seaming rollers to the can cap. A bracket 96 is se- 130

cured to the bottom of the casing 2 and carries a collar 97 through which the shaft 94 passes and to which, said collar is secured by a set screw 98. By means of these devices, 5 the shaft 94 may be adjusted to adjust the seaming rollers so that they will operate accurately to seam a cap to a can.

When the lever 44 is operated to raise the platform 13, the can will be raised and its 10 upper end, in passing through the annular holder 90, will pick up a cap and present the same to the chuck 80 and abutment or holding ring 79. The can and its cap will now be clamped between the platform 13 15 and the chuck 80, so that if the chuck be rotated, the can and its cap will also be rotated. To provide means for rotating the chuck and can, a gear 99 is keyed to the tubular chuck spindle 81 and receives motion 20 from a gear 100 pinned to a driving shaft 101 mounted in a suitable bearing sleeve 102 forming part of the bracket 77. The shaft 101 may be driven from any convenient 25 source of power and suitable manually operable clutch devices may be employed for controlling the operation of said shaft and hence the rotation of the can.

When the parts are in the positions shown in Fig. 4, with the can clamped between the 30 chuck 80 and platform 12, the shaft 101 will be caused to rotate and transmit motion, through the gears 99 and 100, to the chuck spindle, thus causing the rotation of the can and its cap. At the same time, the 35 lever 95 will be operated to bring the seaming rollers into coöperative relation to the flange of the cap and the latter will be seamed to the upper end of the can body.

When the seaming operation shall have 40 been completed, the can will have been hermetically sealed while in the exhausted chamber 3, and the sealed can may then be lowered. The exhaust valve 47 may now be closed and the vacuum release valve 49 45 fully opened, after which the filled and sealed can may be removed.

Various changes might be made in the 50 details of construction of the apparatus without departing from the spirit of my invention or limiting its scope and hence I do not wish to restrict myself to the precise details herein set forth.

Having fully described my invention what I claim as new and desire to secure by Letters-Patent, is:

1. The herein described method, consisting in inclosing within a chamber, an open container having solid food therein, creating a vacuous condition within said chamber

and within the pores of the food in said container, discharging liquid into said container and filling the pores of said solid food, permanently closing and sealing said container, and maintaining a vacuous condition in the chamber in which the container 65 is located during the steps of filling with liquid and permanently closing and sealing the container.

2. The herein described method, consisting in inclosing an open container within a 70 chamber, creating a vacuous condition within said chamber, temporarily closing said container within the vacuous chamber, discharging liquid through the temporary closure into the container without removing the 75 latter from the vacuous chamber, uncovering the container within the vacuous chamber, and sealing the container while the vacuous condition of the chamber in which it is sealed is maintained substantially unbroken.

3. The herein described method, consisting in inclosing within a chamber, an open container, creating a vacuous condition in 80 said chamber, temporarily closing said container within the vacuous chamber, discharging liquid through the temporary closure into the container while in the vacuous chamber, reducing the vacuous condition in the chamber to adjust the degree of vacuum 90 therein to correspond approximately to the degree of vacuum in the filled container, uncovering said container, and then permanently closing and sealing said container while the vacuous condition of the chamber 95 in which it is located is maintained substantially unbroken.

4. The herein described method consisting in inclosing an open container within a 100 chamber, creating a vacuous condition in said chamber, temporarily closing said container while within the vacuous chamber, reducing the internal capacity of the container, then discharging liquid through the closure into said container while the latter 105 is in the vacuous chamber, opening the container, increasing its internal capacity, and sealing the container while the vacuous condition of the chamber in which it is located is maintained substantially unbroken.

In testimony whereof, I have signed this specification in the presence of two subscribing witnesses.

ADOLPH K. MALMQUIST.
